UNITED STATES PATENT OFFICE.

RICHARDS P. McELRATH, OF LAKEWOOD, OHIO.

DESIGN FOR A PNEUMATIC TIRE.

55,630.

Specification for Design.

Patented July 6, 1920.

Application filed May 26, 1919. Serial No. 299,998. Term of patent 14 years.

To all whom it may concern:

Be it known that I, RICHARDS P. McELRATH, a citizen of the United States, residing at Lakewood, the county of Cuyahoga and States of Ohio, have invented a new, original, and ornamental Design for a Pneumatic Tire, of which the following is a specification, reference being had to the accompanying drawings, forming a part thereof.

In Figure 1 is a plan view of the pneumatic tire.

Fig. 2 is a perspective view of the tire as seen from on one side.

Fig. 3 is a transverse section showing my pneumatic tire.

I claim:

The ornamental design for a pneumatic tire, as shown.

RICHARDS P. McELRATH.
